UNITED STATES PATENT OFFICE.

TERENCIO PARINI, OF CANADA ROSQUIN, ARGENTINA.

SCREEN.

Application filed November 12, 1923, Serial No. 674,411, and in Argentina July 23, 1923.

This invention refers to adjustable screens and its object is to provide screens and winnowers, the orifices or mesh of which may be adjusted to various sizes, so that one screen alone may be used to sift various materials or for sorting various sizes of the same material.

Up to now, sieves for screening any kind of material or sorting the same according to size, have been made with orifices or mesh of a set size incapable of variation in any particular. It is readily understood that to form a screen of the mesh of any certain cloth or woven wire, or by punching holes in a sheet of metal, is to construct a sifter the orifices of which remain changeless and non-adjustable. Hence, a different sifter is required for each kind and size of grain or other material it is desired to sift.

For example: In the cleansing and sorting of grains by threshing machines and winnowers, it is necessary to change the screens for each species of grain, and there must be a number of screens of differing degrees of fineness or coarseness, corresponding to the different sizes of seeds borne by different grains or different specimens of the same cereal, as they occur in natural growth. Not only is the changing of the screens an inconvenience and a loss of time, but it adds materially to the cost of the machine.

The present invention obviates these disadvantages entirely. It consists essentially in superimposing and securing two like screens one upon the other in such a manner as to allow their relative displacement to a point where the orifices of the one and the other coincide more or less, as the size of the orifices resulting from their superposition is to be larger or smaller.

The above principle is applicable to screens of all kinds, sizes and shapes.

So that this invention be clearly understood and its practical use be easily perceived, an example is presented in the accompanying drawings, in which:

Figure 1 is a sectional view of the screen with flat surface, fully setting forth the basic principle of the invention.

Figure 2 is a plan view of a part of the screen with corrugated surface, showing the method of its operation.

Figure 3 is a sectional transverse view 55 of the same, at line A—A of Figure 2.

Figure 4 is a sectional longitudinal view of the same at line B—B of Figure 2.

Figure 5 illustrates a section of the screen; and

Figure 6 is a sectional, longitudinal view 60 of the winnower, illustrated in Figure 5, showing the method of its operation.

In all of the above figures, the same reference numbers indicate the same or corresponding parts of the invention.

Figure 1, which illustrates the principle of the invention, shows the superposition of the plane surfaces, 1 and 2, provided with orifices 3, which orifices, though here shown to be circular, may likewise be of any convenient form. Each surface by itself thus constitutes an ordinary sieve, and by superposing those two like sieves and moving one on the other, new orifices are formed smaller than those in either surface. To produce 75 and guide this movement of one surface relatively to the other, use may be made of any kind of controller and, according to the extent of the movement, any size orifice may be produced.

The principle of this invention may be developed as appears in the following examples, though its use is by no means limited to such application.

Figures 2, 3 and 4 show the principle of 85 my invention applied to a thresher screen with corrugated surface. It comprises two plates or surfaces, 1 and 2, the lower of which (2) is non-movable and secured to jambs 4; the upper surface (1), being less in 90 width than the lower, slides on the lower as far as may be desired, along the troughs of the corrugations which fit closely into one another, as may be seen in Figure 4. In the drawings, orifices 3 are shown in the troughs 95 of the corrugations; but it is evident that they may be disposed on the crests or in the sides.

The upper surface slides over the lower by means of a crank, 7, turning between jamb 4 and retaining rim 6. Crank 7 moves between guide 8 and inner jamb 5, which forms the frame for upper surface 1. One end of crank 7 is connected with lever 9, the other extremity of lever 9 being jointed to arm 10, which, on its unattached end, bears a screw-thread passing through eye 11, this eye being conjoint with the frame. Working on the screw-thread, on either side of eye 11, is a thumbscrew 12, by means of which 110

arm 10 may be drawn towards one end of the screen or the other, drawing with it that end of lever 9 which is attached to itself (10). The other end of lever 9, jointed to crank 7, communicates the movement to the latter member, the position of which determines the greater or less coincidence of orifices 3.

Figures 5 and 6 show an example of my invention developed with concentric cylindrical screen surfaces 1 and 2, perforated by slits 3. These cylinders move one within the other longitudinally, to the width of one slit (3). This movement is induced as follows:

At the ends of external cylinder 1 are disposed rods 14, the extremities of which are fixed to frame 13 and, midway between their ends, these rods pass through rotating shaft 15; one end of this shaft, at the point where rod 14 passes through it and on either side of that point, bears screw-thread 16, on which turn thumbscrews 16'.

Internal cylinder 2 is mounted on rods 19, which, midway between their ends, are fixed to shaft 15; these ends of rods 19 are secured to jambs 18 and these to frame 17.

The relative position (and consequently the size of apertures 3) is changed by loosen-

ing one of the thumbscrews 16' and tightening the other.

It must be clearly and insistently understood that the form of the screens, and the exact mode of their actuation are not limited by the examples here given, said examples being introduced merely to display the application of a principle new in the art, and the scope of which is clearly defined in the following claim.

Having thus described my invention, what I claim is:

An article of the character described, comprising a pair of corrugated perforated plates super-imposed the one upon the other, whereby the corrugations of said plates serve to guide one another when movement is given to said plates, a frame for mounting each plate, a guide mounted on one of said frames, a crank arranged to cooperate with said guide, whereby when the guide is actuated one plate slides over the other, and means connected to said crank and to one of the said frames to retain the plates in any desired position relatively to each other.

In testimony whereof I affix my signature.

TERENCIO PARINI.
